SMOKING PIPE

Arch MacDonald, Seattle, Wash.

Application May 31, 1940, Serial No. 338,171

3 Claims. (Cl. 131—196)

This invention relates to tobacco smoking pipes, and has for its principal object to provide improvements in pipes that will overcome undesirable heating of the bowl and stem and will result in a cooler smoke than is usually obtained from use of pipes of this type.

It is also an object of this invention to overcome heating of the pipe bowl by providing it with inner and outer walls, or what I refer to as shells, enclosing an insulating air chamber between them.

Another object of the invention resides in the details of construction and relationship of the various parts of the bowl, to insure against the transmission of heat from the interior to the exterior shell and in the manner and means for securing the parts together in assembled relationship and functionally attached to the stem.

Still another object of this invention resides in the provision of a stem of novel construction, provided with a relatively large chamber in which the intaken smoke will be cooled prior to its being drawn out.

It is still another object to provide for easy interchange or replacement of the inner shell of the pipe bowl.

Still further objects of the invention reside in the details of construction of parts embodied in the stem, and in a special clean-out device associated therewith.

In accomplishing these, and other objects of the invention, I have provided the improved details of construction, the preferred forms of which are illustrated in the accompanying drawing, wherein—

Fig. 1 is a side view of a smoking pipe embodied by the present invention.

Fig. 2 is a view of those parts which are embodied in the stem portion of the pipe, showing them in disconnected relationship, and partly in section.

Fig. 3 is a longitudinal, sectional view of the pipe.

Fig. 4 is an enlarged side view of parts of the clean-out device, shown in disconnected relationship.

Fig. 5 is an enlarged, cross sectional view of the pipe bowl.

Fig. 6 is a view of a pipe bowl of an alternative form.

Referring more in detail to the drawing—

The present pipe is designated in its entirety by reference numeral 1, and it comprises a bowl assembly 2 and a stem assembly 3. The bowl assembly includes those parts which are comprised

in the outer shell, the inner shell and the devices whereby the parts of the bowl are held assembled and secured to the stem. The stem assembly includes the stem barrel, the mouthpiece and the clean-out device.

First, describing the bowl assembly, especially with reference to Fig. 5, in which its structure is best shown: 5 designates the inner shell, which is designed to receive the tobacco. This is of cup-like form, open at the top and closed at the base by a wall 5' which may be of the rounded form shown in Fig. 5, or of the conically tapered form of the shell 5a shown in Fig. 3. In the center of the bottom wall 5' of the bowl is a hole 6 for reception of an attaching screw 7, which will later be described more in detail; and, about its upper periphery, the shell is formed with an encircling, outwardly projecting flange 8.

The outer shell of the bowl comprises a metal base 9 and an upper member 10. The member 10 is of truncated-conical form, and is formed about its upper edge, at the inside, with an inwardly facing seat 11 adapted to receive the base surface of the annular flange 8 of the inner shell thereagainst, so that, when the latter is seated therein, the upper ends of these parts will be flush and a tight connection is provided.

The base section 9 is of disk-like form, preferably of metal, and provided with a central hub or neck 12 with an opening through which a tubular screw 13 is threaded. This screw is both interiorly and exteriorly threaded and has a flanged head, or upper end portion 14, which is seated against the inner surface of the piece. The lower end portion of the screw 13 extends below the base of the piece 9, and, as later will be understood, serves to attach the bowl assembly to the stem assembly.

The upper peripheral edge portion of the base 9 is formed with an upturned flange 15 which seats against a downwardly facing annular seat 16 formed about the lower end of the part 10 at the outside thereof. When the parts 5, 9 and 10 of the bowl are functionally assembled, with the peripheral edge flange 8 of the inner shell seated against the upper end shoulder 11 of the part 10, and the lower end of part 10 seated upon the upper edge flange 15 of the metal base 9, and the hollow screw 13 in place, then all may be secured together by the application of the screw 7 that is extended down through the central hole 6 of the inner shell and is threaded into the hollow or tubular screw 13. The screw 7 is hollow and has an annular flange 18 about its upper end adapted to overlap the bottom wall of the shell 5 about

hole 6 to form a tight joint and to clamp the parts tightly together. The screw 7, being hollow from end to end, forms a channel for passage of smoke from the bowl into the stem.

To facilitate the application of the hollow screws 7 and 13, each is formed across its head end with a channel, as at 19, for reception of a screw driver bit.

With the parts so shaped and assembled, it is to be noted, especially by reference to Figs. 3 and 5, that an air chamber 20 is thus provided between the inner and outer shells. This chamber may be ventilated by the provision of air ports 21 through the base and upper sections 9 and 10 to facilitate the cooling effect. The insulating effect of the air chamber is apparent.

The stem assembly, as observed best in Figs. 2 and 3, comprises a tubular barrel portion 25 of relatively large inside capacity, open from end to end. Set in the top wall of this barrel, near one end, is a metal collar 26, having a threaded hole for reception of the threaded lower end of the hollow screw 13 to functionally attach the bowl to the stem, and when these parts are assembled, the lower end of the screw is substantially even with the chamber wall. At its bowl mounting end, the barrel is closed by a threaded plug 27 formed with a head 28 that may be knurled to add decorative effect thereto.

The barrel 25 preferably is formed of a plastic material, and is slightly outwardly flared from the bowl end, to mouth-piece end, and at the latter end has a metal sleeve 30 fitted and cemented therein. This sleeve has an end flange 30' of a decorative character, that limits its extent of seating within the barrel. A mouthpiece 32 is removably fitted in the sleeve, and this has a channel or bore 34 which, at its inner end, mounts a small tube 35 that extends beyond the inner end of the mouthpiece and is provided, as noted in Figs. 2 and 3, with ports 36 for entrance of smoke.

Threaded into the end of the tube 35, but not to an extent to obstruct the ports 36, is a rod 40 that extends axially of the barrel, as seen in Fig. 3, and terminates just short of the bowl connection, and is there provided with a metal ball 41, and a disk 42 of a diameter that closes the barrel at that point. The disk is formed with a plurality of small ports 43 for passage of the smoke. In this assembled relationship of parts, smoke drawn into the barrel from the bowl first contacts the metal ball and this aids in condensing the moisture in the smoke; the smoke then passing through ports 43 into the larger chamber of the barrel and then to the mouth-piece channel through the ports 36. The small chamber between the disk 42 and plug 27 retains the moisture.

In Fig. 6 has been shown an alternative bowl structure in which there is a flanged metal collar 50 applied about the upper end of the inner

shell 5 and this has a flange 51 for seating against the shoulder flange 8, and has a down-turned flange 52 overlapping the upper end of the section 10. This collar may be more desirable in some instances, due to its ornamental quality.

Since it is intended that pipes of this character be made up in plastic, it is possible to make them in many different designs and in many combinations of attractive colors. Furthermore, the fact that the inner shell is easily removable or replaceable, makes it practical to form these shells of a material that adds to smoking comfort, such, for example, as corn cob, which is inexpensive and very desirable from the standpoint of the smoker.

Having thus described my invention, what I claim as new therein and desire to secure by Letters Patent is:

1. In a pipe of the character described, a bowl comprising an inner shell formed with a bottom wall opening, an outer shell spaced from the inner shell with respect to the major portion thereof and providing an intermediate air chamber between them and having a bottom wall opening, and a hollow screw extended through said openings of the inner and outer shells for mounting the bowl on a stem and having a head engaging in clamping contact with the inner shell about the bottom opening therein to hold the parts functionally assembled.

2. In a pipe of the character described, a stem having a smoke chamber therein and a mouth-piece applied to the stem for drawing smoke from the chamber, and a bowl assembly comprising an outer shell, an inner shell applied within the outer shell to provide an intermediate air chamber; said inner and outer shells having registering openings in their bottom walls and a hollow screw extended through said openings and threaded into the stem to mount the bowl on the stem and to form a smoke channel from the bowl into the stem.

3. In a pipe of the character described, a pipe stem having a smoke chamber, and having a top opening into one end of the chamber, a bowl comprising an outer shell and an inner shell forming an intermediate air chamber; said outer shell comprising a base member with a central opening and a top member mounted on the base member, a hollow screw extended through the said central opening of the base member and threaded into said stem opening to attach the base member to the stem; said inner shell having a holding connection about its top edge with the top section of the outer shell and having a base opening, and a hollow screw extended through said base opening and threaded into the first mentioned screw to secure the two shells functionally together, and providing a smoke passage from the bowl into the stem.

ARCH MACDONALD.
